UNITED STATES PATENT OFFICE

CLINTON S. BUDD, OF CLARION, PENNSYLVANIA, ASSIGNOR TO HARTFORD-EMPIRE COMPANY, OF HARTFORD, CONNECTICUT, A CORPORATION OF DELAWARE

MULTIPLE PRESS HEAD FOR GLASSWARE-SHAPING MACHINES

Application filed November 3, 1925. Serial No. 66,513.

My invention relates to glass pressing apparatus and it has special reference to apparatus for pressing the finish openings of hollow glass articles made by pressing or by 5 pressing and blowing.

In the manufacture of bottles, jars and other hollow glassware, the top opening or finish of the article is frequently made by inserting a plunger into a mold containing a 10 charge of molten glass, the plunger and the mold being suitably shaped to produce the finished contour of the neck or other top opening of the article, which is termed the "finish." The body of the article may be completed by 15 the same pressing operation, or the pressing operation may produce an intermediate blank or parison in which only the finish is completed, the body of the article being thereafter expanded by blowing.

20 Milk bottles, jars and other kinds of pressed or pressed and blown glassware are now made in a great variety of shapes, and articles of the same general size and shape are made with various finishes. Each individual finish must be produced with a plunger and a 25 mold made for that particular finish. The matter is further complicated by the fact that bottles and jars of this class are often made to fill comparatively small orders, and it is 30 therefore desirable to provide the manufacturer with means for making articles having more than one finish, upon a single automatic machine and during the same operation of the machine.

35 My present invention aims to satisfy these requirements by providing a press head having a plurality of pressing plungers of different shapes suited to the finishes to be produced, and by so arranging a press head that 40 the plungers of different shapes cooperate successively with the molds of a glassware shaping machine.

In the specific embodiment of my invention herein shown and described, two pressing plungers are shown for convenient illustration, and the press head carrying these plungers is arranged to swing periodically in response to the movement of the mold table to bring the plungers alternately or alternatively to the pressing station. At this station

each plunger cooperates with a mold having a finish shape corresponding to the shape of that particular plunger, and the apparatus so equipped is therefore able to produce articles of two different neck-finishes in one 55 operation of the same machine. The invention may also be carried out with three or more plungers of different shapes, as will more fully appear below.

50 In the accompanying drawing: Figure 1 is a plan view of a multiple press head constructed and operated in accordance with my invention, this apparatus being shown in connection with a portion of a rotary mold table;

55 Fig. 2 is a side elevational view, with parts in section, of the apparatus shown in Fig. 1; and

60 Fig. 3 is a side elevational view of the press head as seen from the right of Figs. 1 and 2, the mold and the mold table being shown in section.

65 In the drawing, the numeral 2 represents a holder which is secured to, and projects horizontally from, a swinging frame composed of an upper plate 3 to which the holder 2 is bolted, a lower member 4, vertical connecting members 5 and 6 secured adjustably together by means of a bolt 7, and bearing members 8 and 9 that are mounted for vertical adjustment and for swinging movement upon a vertical shaft 10. The vertical position of the frame is fixed by a collar 11 surrounding the shaft 10 below the bearing 9 and secured to the shaft by a set screw 12.

70 An extension spring 13 has one of its ends connected at 14 to the member 4 of the press head frame and its other end is connected to any convenient fixed support 15. This spring tends to hold the frame against a 75 fixed stop member 16.

75 The holder 2 carries two pressing plunger mechanisms for cooperating with the molds upon a rotary mold table 20. The portion of the table shown in the drawing carries 80 two molds 21 and 22 which, as shown, are suitable for making milk bottle parisons having slightly different neck-finishes, and the table is rotated in a step-by-step manner in the direction of the arrow in Fig. 1, so as to 85 90 95 100

bring the molds successively to the position occupied in the drawing by the mold 21, which is the pressing station of the machine. For the present purposes it may be assumed that the mold 21 is one of a series of molds 5 having identical neck finishes, and that these molds are alternated with an equal number of molds 22 having different neck finishes. A lug 23 projects from the mold table 20 somewhat in advance of each of the molds 22.

As shown herein by way of illustration, each of the plunger mechanisms carried by the holder 2 comprises a central stem 24 and three rods 25 arranged triangularly around 15 the central stem 24, the stem and the rods extending through the holder 2. The rods 25 also extend at their upper ends through a triangular plate 26, beneath which is secured a thimble 27 into which a thimble 28 is adapted 20 to enter from above. A spring 29 is contained within the enclosure formed by the thimbles 27 and 28. Springs 30 surround the vertical rods 25 between the plate 26 and nuts 31 applied to the rods 25. A main 25 spring 32 surrounds the central stem 24 between the holder 2 and the under side of the thimble 27.

To the lower end of the central stem 24 below the holder 2 is secured a plunger holder 33 in which is clamped a plunger 36. The plunger is surrounded near its lower end by a plunger ring 37 carried by a plate 38 that is removably secured by means of a clamp 39 to a plate 40 which is carried by 35 the lower ends of the vertical rods 25.

For the purpose of depressing the plunger mechanism, I provide an air cylinder 41 having a piston 42 and a piston rod 43 which is disposed above and in line with the 40 axis of the mold at the pressing station and also in line with the axis of the pressing plunger which, at any given time, is at the molding station. The cylinder is provided with ports 44 and 45 for admitting and exhausting fluid pressure. Downward movement of the piston rod 43 is transmitted to the plunger beneath the cylinder through a stem 46 which projects upward from the thimble 28 of the plunger mechanism.

50 When the piston rod 43 depresses the stem 46, this movement is transmitted through the spring 29 to lower the plate 26 and the plunger 36 and plunger ring 37 carried thereby. The lowering movement of the plate 26, 55 plunger 36 and plunger ring 37 first seats the plunger ring in the cavity 47 of the mold 21. Continued movement of the plate 26 causes no further movement of the plunger ring 37, but causes a differential movement of rods 60 25 and plate 26, which causes the rods 25 to slide through the apertures in the plate, compressing the springs 30. This continued movement also causes the plunger 36 to be lowered within the mold 21 and to force 65 the glass to conform to the shape of the mold

and complete the neck finish of the glass article, this movement being transmitted through the spring 29 and serving to compress the spring 32. When the rod 43 of the operating cylinder rises, the plunger 36 70 will first be withdrawn out of engagement with the glass by the expansion of the spring 32, the plunger ring 37 remaining in cooperative relation with the mold 21 until the reverse differential movement of the rods 25 75 and plate 26 brings this plate into engagement with the nuts on the upper ends of the rods. Thereafter the plunger ring 37 and plunger 36 will be raised upward together to the position shown in Fig. 2 by the further expansion of the spring 32.

The specific plunger structure just described is shown merely as an example of suitable plunger mechanism, and it will be understood that any other suitable plunger 85 arrangement may be employed.

As soon as an article has been pressed in the mold 21 at the pressing station, the table 20 is advanced to bring the mold 22 to the pressing station. During this advancing movement of 90 the table, the lug 23 strikes a lug 50 which projects from the lower member 4 of the press head frame. The remainder of the table movement causes the lug 23 to carry with it the lug 50, thereby swinging the press head frame around the shaft 10 to bring the other press head to position above the pressing station. The article is pressed in the mold 22 in the manner described above, after which the table 20 advances another step. During the 95 first part of this movement, the lugs 23 and 50 are still in contact and, therefore, the press head is swung a short distance beyond the pressing station until the lug 23 releases the lug 50, whereupon the spring 13 swings the frame back until it strikes the fixed stop member 16, thereby bringing the press head to its original position, as shown in the drawing.

In order to reduce the shock of engagement 100 between the lug 23 and the lug 50, the lug 50 is mounted pivotally at 51, as shown in Fig. 1, and its rear end bears, through a member 52, against the end of a spring 53 contained in an opening in the lower member 4 of the press head frame. This opening is closed by a screw 54 which regulates the tension of the spring 53.

The lugs 23 and 50 may suitably be made of hardened steel having knife edges to reduce the amount of contact between these members. The amount to which the press head is swung beyond the pressing position after the second molding operation described above is determined by the amount of overlap between the lugs 23 and 50, and this overlap may be varied to enable the use of three or more plungers on the same press head. Various other means may be adopted for using more than two plungers. For example, two sets of lugs may be provided in different vertical positions and 115 120 125 130

having differences of overlap, and also having different positions of the lugs relative to the molds, so that the head may move to a third or fourth position, if necessary.

5 I am aware that it has been proposed to provide a glassware pressing machine with multiple plungers, but such multiple plungers have heretofore been provided only for the purpose of preventing overheating of the 10 plungers which are brought into use successively. In such cases, all of the plungers have been identical in shape and have cooperated with molds also identical in shape. I consider that it is broadly novel with the present invention to provide a press head having two or more plungers of different contours with means for bringing the plungers into action successively to produce articles of glassware having different neck finishes.

20 My invention has been found to be useful in the manufacture of milk bottles and other articles made by pressing or by pressing and blowing. It is useful not only in the production of wide-mouth and semi wide-mouth 25 ware, but in the production of narrow-neck bottles.

While the structure shown in the accompanying drawing has been found to be well suited for carrying my invention into actual 30 practice, it will be understood that numerous changes in the construction and arrangement of parts may be made without departing from my invention as set forth in the appended claims.

35 I claim as my invention:

1. Glass-working apparatus comprising a rotary mold table, molds carried thereby, lugs carried by said table in advance of certain of said molds, a press head mounted to swing 40 on a horizontal axis, a plurality of pressing plungers carried by said press head and movable successively to a position above a pressing station to which said molds are brought by the rotation of said table, a lug carried by 45 said press head and adapted to be engaged by said first named lugs to swing said press head from a position in which one of said plungers is at the said pressing station to a position where another of said plungers is at 50 the said pressing station, and a spring for returning said press head to its initial position when said lugs are disengaged.

2. The combination with a glass making machine having a blank mold and a plunger 55 device cooperating therewith to form a blank therein, of means for altering the plunger device to form dissimilar blanks during selected operations of said plunger device.

60 3. The combination with a glass making machine having a blank mold and a plunger device cooperating therewith to form a blank therein, of means for automatically altering the plunger device to form dissimilar blanks during selected operations of the said plunger device.

4. The combination with a glass shaping machine having a blank mold member and a plunger member cooperating therewith to form a blank, of means for altering one of said members to form dissimilar blanks during selected operations of the said members. 70

5. The combination with a glass shaping machine having blank molds, and a forming member cooperating therewith, of means for altering the forming member to form dissimilar blanks during the operation of the shaping machine. 75

6. In combination in a glass shaping machine provided with blank molds successively presented to a pressing station, blank forming apparatus at said station adapted to cooperate with said molds and having a plurality of neck forming parts of different configurations, means for causing the cooperation with successive molds of different neck 80 forming parts of said apparatus. 85

7. In combination in a glass shaping machine having blank molds, means for forming in successive molds glass blanks having different configurations, comprising pressing 90 mechanism adapted to close the blank molds and to press the glass therein, having a plurality of ware-shaping parts of different configurations, and means acting while the shaping machine is operating for presenting to the successive molds different ware shaping parts 95 of said pressing mechanism.

8. In combination in a glass shaping machine having blank molds, a pressing head and means for moving the same toward and 100 from the molds, a plurality of blank shaping members mounted on said pressing head and cooperating with said molds to form blanks, and means for causing different shaping members to cooperate with successive molds 105 to form blanks of different configurations therein.

9. The combination with a glass making machine having a blank mold and a plunger device cooperating therewith to form a blank 110 therein, of means for altering the plunger device to form dissimilar blanks during selected operations of said plunger device, said means comprising a lug mounted for movement in a circular orbit, and cooperating means associated with said plunger device for altering said device in response to the movement of said lug through a predetermined portion of its orbit. 115

10. The combination with a glass shaping machine having blank molds, and a forming member cooperating therewith, of means for altering the forming member to form dissimilar blanks during the operation of the shaping machine, said means comprising a plurality of lugs each placeable selectively upon a moving part of said machine in predetermined relation with any one of said molds, means cooperable with said lugs for causing said forming member to cooperate 120 125 130

with the molds thus associated with said lugs to form blanks of one configuration, and means for causing said forming member to cooperate with the remaining molds to form blanks of another configuration.

11. The combination with a glass shaping machine having blank molds, and a forming member cooperating therewith, of means for altering the forming member to form dissimilar blanks during the operation of the shaping machine, said blank molds being successively brought to a position for cooperation with said forming member in recurring cycles, and said means being such as to form blanks in certain of said molds of one form and to alter the forming member for enabling it in cooperating with the remaining molds to form blanks of another form therein, whereby on each complete cycle of said molds, predetermined numbers of blanks of two different forms will be formed.

12. In combination in a glass shaping machine provided with blank molds successively presented to a pressing station, blank forming apparatus at said station adapted to cooperate with said molds and having a plurality of neck forming parts of different configurations, means for causing the cooperation with successive molds of different neck forming parts of said apparatus, a rotatable carrier about which said blank molds are arranged, and said molds including molds of at least two different internal configurations, and said means being operable selectively to cause the cooperation with the molds of one configuration of forming apparatus having one configuration of its neck forming parts and with molds of the other configuration of the forming apparatus having another configuration of its neck forming parts, whereby a plurality of different shaped articles are formed on each complete revolution of said carrier.

Signed at Clarion, Pa., this 7th day of
45 October, 1925.

CLINTON S. BUDD.
